US0D1060266S

(12) **United States Design Patent** (10) **Patent No.:** **US D1,060,266 S**
(45) **Date of Patent:** **** Feb. 4, 2025**

(54) **CHARGING CONNECTOR**

(71) Applicant: **BLACK & DECKER INC.**, New Britain, CT (US)

(72) Inventor: **Timothy J. Payne**, Columbus, OH (US)

(73) Assignee: **BLACK & DECKER INC.**, New Britain, CT (US)

(**) Term: **15 Years**

(21) Appl. No.: **29/871,469**

(22) Filed: **Feb. 21, 2023**

(51) **LOC (15) Cl.** **13-03**

(52) **U.S. Cl.**

USPC **D13/146**; D13/107

CLAIM

The ornamental design for a charging connector as shown and described.

DESCRIPTION

FIG. 1 is a front perspective view of a charging connector according to the invention.

FIG. 2 is a front view of the charging connector of FIG. 1.

FIG. 3 is a rear view of the charging connector of FIG. 1.

FIG. 4 is a right side view of the charging connector of FIG. 1.

FIG. 5 is a left side view of the charging connector of FIG. 1.

FIG. 6 is a top plan view of the charging connector of FIG. 1; and,

FIG. 7 is a bottom plan view of the charging connector of FIG. 1.

The broken line showing of the charging connector is for the purpose of illustrating environmental structure and forms no part of the claimed design.

1 Claim, 5 Drawing Sheets
